UNITED STATES PATENT OFFICE.

EDWARD J. GLACKIN, OF CHICAGO, ILLINOIS.

SHOCK-ABSORBER.

1,249,064.

Specification of Letters Patent.

Patented Dec. 4, 1917.

Application filed April 17, 1916. Serial No. 91,509.

To all whom it may concern:

Be it known that I, EDWARD J. GLACKIN, a citizen of the United States, and a resident of Chicago, in the county of Cook and State of Illinois, have invented certain new and useful Improvements in Shock-Absorbers, of which the following is a full, clear, and exact specification.

My invention is concerned with shock absorbers, such as are ordinarily used in connection with the body supporting springs of automobiles to take up the shocks resulting from driving rapidly over rough roads, and it is designed to produce a single device of the class described which will be capable of responding to compression or tension, as the case may be, wherever it is applied, thus increasing its efficiency and utility over the ordinary structure which can work either under compression or tension, as it may be designed or located, but not under both.

To this end, my invention is embodied in certain novel constructions and combinations of elements, all as will be set forth in the specification and particularly pointed out in the claims.

To illustrate my invention, I annex here-to two sheets of drawings in which the same reference characters are used to designate identical parts in all the figures, of which—

Figure 1 is a side elevation showing a shock absorber embodying my invention, located between the ends of a body-supporting spring and side bar of a vehicle;

Fig. 2 is a view, on an enlarged scale, partly in section, as it would appear on the line 2—2 of Fig. 1;

Fig. 3 is a view in section as it would appear on the line 3—3 of Fig. 2;

Fig. 4 is a plan view as it would appear in section on the line 4—4 of Fig. 3; and

Fig. 5 is a perspective view of the yoke members of the upper side detached from the associated members.

In carrying out my invention in its preferred form, I employ a pair of outer yokes 10 and 11, the upper outer yoke being best seen in perspective in Fig. 5, where it will be seen to have the bar-like base portion 12 with the two perforated bearing ears 13 projecting upward therefrom, so that the

yoke can be suspended by the bearing pin 14 from the outer end of the body side bar 15. It has the downwardly projecting arms 16 forming the fork of the yoke, and each arm is provided with one member of a slot and pin connection, the member shown being the slot 17. The lower yoke member 11 is somewhat different in shape owing to the fact that its arms 16^a preferably stand substantially at right angles to the arms 16 when both are referred to the common axis of the yokes, and consequently the base portion 12^a is in the form of a cross with the arms 16^a projecting upward from two ends of the cross, while the bearing ears 13^a project downward from the other end of the cross to receive the bolt or pin 14^a by which the lower yoke is secured to the outer end of the body spring 15^a. The arms 16^a of the lower outer yoke 11 are provided with their members of the slot and pin connection, which in the illustration shown are the pins 17^a.

Inside of the outer yokes 10 and 11 are a pair of inner yokes 18 and 19, both of which are provided with bases 20 and 20^a, respectively, which bases are preferably circular in form, and have the short arms 21 and 21^a respectively projecting therefrom to support the vertical arms 22 and 22^a, each of which are provided on their inner ends with slot and pin elements, the arms 22 in the form illustrated being provided with the slots 23, which coöperate with the pins 17^a of the lowermost outer yoke 11, while the arms 22^a are provided with the pins 23^a which coöperate with the slots 17 in the arms of the uppermost outer yoke 10. It will be understood from the foregoing connections that the arms of each of the outer yokes are set at an angle of 90° to the corresponding arms of the opposed outer yoke, while the arms of each of the inner yokes are likewise set at an angle of 90° to the arms of the opposed inner yokes, the arms of the outer yokes being thus telescopically connected with the arms of the directly opposed inner yokes.

With the arrangement herein described, it will be obvious that if a cushioning element be interposed between the bases of the inner yokes, said cushioning element will be com-

pressed, whether the outer yokes be drawn away from each other or pushed toward each other. When they are drawn away from each other, the pins 17^a and 23^a are held at the inner ends of the coöperating slots 23 and 17, and as a consequence, the heads 20 and 20^a of the inner yokes are pulled together by the diverging movement of the outer yokes. On the other hand, 10 when the outer yokes are pushed together, their bases 12 and 12^a rest on the bases 20 and 20^a of the inner yokes, respectively, and force them together, this movement being permitted by reason of the slot and pin connections between the arms of the outer and inner yokes.

As a preferred form of a cushioning element, I employ a rubber sack 24 which has the inflating valve 25 secured in one end thereof, and in the boss 26 of the base 20 of the upper inner yoke, through which the valve passes. To protect the sack, I form the telescoping cup members 27 and 27^a, projecting downward and upward from the circular bases 20 and 20^a, respectively, from the two inner yokes. To preserve the bag from moisture and wear I preferably surround it by a water-proof canvas bag 28 and by varying the pressure of the air in the bag, I am able to control the resiliency of the shock absorber.

As another form of cushioning element which I may employ with or without the rubber sack 24, I have shown the helically coiled expanding spring 29 which surrounds the telescoping cups 27 and 27^a, the ends thereof being preferably seated on annular shoulders 30 and 30^a formed on the inner surfaces of the peripheries of the circular bases 20 and 20^a.

While I have shown and described my invention as embodied in the form which I at present consider best adapted to carry out its purposes, it will be understood that it 45 is capable of modifications, and that I do not desire to be limited in the interpretation of the following claims, except as may be necessitated by the state of the prior art.

What I claim as new and desire to secure 50 by Letters Patent of the United States is:

1. In a device of the class described, the combination with a pair of telescoping elements, each provided at one end with means to secure it to one of a pair of supporting elements, of telescoping connections between said telescoping elements which prevent their entire separation but allow them to approach each other, and a cushioning element disposed between said telescoping elements and put under compression whether the securing means of the two telescoping elements are drawn apart or pressed together, said cushioning element consisting of an inflated air-tight sack interposed between said telescoping elements, which are

unyielding and fit so snugly about the sack as to prevent its yielding outward in any direction when it is compressed by the approach of said elements.

2. In a device of the class described, the combination with a pair of telescoping elements, each provided at one end with means to secure it to one of a pair of supporting elements, of telescoping connections between said telescoping elements which prevent their entire separation but allow them to approach each other, and cushioning elements disposed between said telescoping elements and put under compression whether the securing means of the two telescoping elements are drawn apart or pressed together, one of said cushioning elements consisting of an inflated air-tight sack interposed between said telescoping elements, which are unyielding and fit so snugly about the sack as to prevent its yielding outward in any direction when it is compressed by the approach of said elements, and the other consisting of a helically coiled expanding spring surrounding the cushion and similarly compressed between annular opposed flanges formed on the outer ends of the telescoping elements.

3. In a device of the class described, the combination with a pair of outer opposed yokes standing at different angles to the common axis, each provided at its outer end with securing means and on its inner ends with one element of the slot and pin connection, of a pair of inner opposed yokes situated within the first-mentioned pair but at an angle to the adjacent outer yoke, each of said inner yokes having the other element of a slot and pin connection on its inner end coöperating with the slot and pin element of the directly opposed outer yoke, and a cushioning element interposed between the inner yokes and put under tension whether said outer yokes are pulled away from each other or pushed toward each other.

4. In a device of the class described, the combination with a pair of opposed outer yokes standing at different angles to the common axis, each provided on its base with a pair of ears and having on its inner ends one element of a slot and pin connection, of a pair of opposed inner yokes within the outer yokes standing at different angles to the common axis, but directly opposed to the opposed outer yokes, each of said inner yokes provided at its inner ends with the other element of the slot and pin connection with the directly opposed outer yoke, a pair of telescoping cups having their bottoms secured to the bases of the adjacent inner yokes, and cushioning means disposed between said telescoping cups.

5. In a device of the class described, the combination with two opposed elements

movable toward and from each other, of a pair of closely fitting telescoping cups interposed between said elements in such a manner that they are forced together whether the two opposed elements are moved toward or away from each other, and an inflated air-tight sack filling said cups when they are separated and prevented from

yielding outward when they are forced together.

10

In witness whereof, I have hereunto set my hand and affixed my seal, this 14th day of April, A. D. 1916.

EDWARD J. GLACKIN. [L. S.]
